UNITED STATES PATENT OFFICE.

HORATIO S. EARLE, OF CHICOPEE FALLS, MASSACHUSETTS.

PIE-FORK.

SPECIFICATION forming part of Letters Patent No. 392,261, dated November 6, 1888.

Application filed November 16, 1887. Serial No. 255,352. (No model.)

To all whom it may concern:

Be it known that I, HORATIO S. EARLE, a citizen of the United States, residing at Chicopee Falls, Hampden county, State of Massachusetts, have invented a new and useful Improved Pie-Fork, of which the following is a specification.

My improvements relate to that class of pie-forks in which the pie grasped in the fingers of the device is given a rotation upon being lifted from the floor of the oven, and have for their object an increased simplicity of construction and a compactness in the arrangement of the parts, enabling the device to be manipulated in the limited space in which it can only be used to greater advantage.

My invention consists in the combination and construction as hereinafter described, and more particularly pointed out in the claim.

The invention is fully illustrated in the accompanying drawings, in which—

Figure I is a side view, in partial section, of a part of the device. Fig. II is a side view of the same part in a changed position. Fig. III is a plan view of the same; and Fig. IV is a perspective view, in reduced scale, of the complete device in operative position.

Heretofore pie-forks of this class have obtained their rotation by gravity upon lifting the pie, representing the weight, from the oven-floor; but the distance required by the weight to fall in order to obtain a rotation by following the threads of a quick screw has required a vertical offset from the handle, which materially circumscribes the distance to which the fork may be lifted in the limited space of an oven without striking against the roof thereof, in some cases insufficient to enable the device to be worked, whereas on the other hand, when said offset from the handle is downward between the grasping-fingers, it is liable to dig into the crust of the pie before the fingers can stretch far enough apart to grasp the plate, in order to obviate which disadvantages in a very convenient device, as well as to obtain a much quicker rotation to the pie, and so obviate discomfort to the operator, whose hand is within or close to the heated oven, as well as save the heat in the oven by shortening the time necessary for its door to remain open, I construct a rotating device as follows:

B is the finger-carrying bar, having a hole, b, bored vertically therethrough.

C is a rod prolonged from the bar B to form a handle, and having an end, c, bent at right angles to the major length of the rod to pass through the hole b.

d is a washer upon the end c, forming a stop to prevent it from leaving the hole b.

D is a plate secured to the top of the bar B, having a hole therethrough coinciding with hole b axially and of diameter permitting the end c to pass therethrough and turn freely therein. Upon opposite sides of hole b, on plate D, rise two ratchet-teeth, e f, having their vertical faces in the same plane and coinciding with the longer axis of bar B. The tooth e is of a height sufficient to prevent the rod C from ever passing over it, and so forms a stop to prevent the bar B from ever making more than a half revolution or rotation on the end c. The tooth f is shorter than the one e, so that at times it can pass under rod C to permit bar B to rotate. The length of the part e of rod C is proportioned to permit the tooth f to pass under rod C when the bar B is in contact, or nearly so, with the washer d.

h is a coil-spring surrounding the part c, within hole b, having one end secured to the part c at h', and having its other end secured to bar B at i.

m m are fingers secured to the bar B in the well-known manner to operate, as more particularly shown in Fig. IV, by cornering on each side of the pie-plate O, and are released or caused to grasp the plate by a rotary movement given to the handle B.

The operation of my device is as follows: The bar B is rotated by hand to wind up the spring h, and, the tooth f having passed under rod C, the bar B is pushed up slightly to cause the vertical face of tooth f to catch against the side of the rod C. The device is now wound and set, and the weight of the pie coming upon bar B pulls the catch free from rod C, and the coil-spring revolves the bar B until the tooth e, bringing up against rod C, stops the pie at a half-rotation. The spring may be made as strong as desired, and the catch formed by tooth f be proportioned in sensitiveness to the strength of the spring. A positive movement in rotation can be thus im-

parted to bar B to rotate it much quicker than by gravity, and the projection of end *c* below the face of bar B need be no greater than the catch-tooth *f*, required to be cleared by the rod.

5 Now, having described my invention, what I claim is -

The within-described improved pie fork, consisting of a finger-bearing bar, B, provided with fingers adapted to embrace a pie-plate, 10 and having aperture *b* therethrough; a handle-rod, C, having end *c*, passing through bar B, a stop upon end of end *c*, projecting beyond bar B, a coil-spring wound around end *c* within hole *b*, having one end thereof secured to end

c and the other fast to bar B, and two stops, 15 *e f*, of unequal length, arranged upon opposite sides of hole *b*, the one forming a permanent stop and the other an intermittent one relative to rod C, substantially as shown and described, whereby the spring may 20 be wound and the bar set upon one stop to be released by the weight of the disk to rotate the bar to the other stop, all arranged as and for the purpose set forth.

HORATIO S. EARLE.
